UNITED STATES PATENT OFFICE.

LEO D. JONES AND ARTHUR U. AYRES, OF PHILADELPHIA, PENNSYLVANIA, ASSIGNORS TO THE SHARPLES SPECIALTY COMPANY, OF PHILADELPHIA, PENNSYLVANIA, A CORPORATION OF DELAWARE.

CENTRIFUGAL BOWL.

Application filed September 4, 1925. Serial No. 54,477.

Our improvements are designed to provide means for securing heads or end closures to the shells of bowls of centrifugal machines so as to effectively seal the joints 5 between the parts and secure coincidence and alignment of the axes of the closures with the axes of the bowl.

Leading objects of our invention are to obviate the play and loss of alignment between a bowl and its head; to avoid leakage incident to the use of usual threaded, welded or packed joints; to avoid the melting, deterioration or displacement of solder or of packing commonly used; and to avoid the shell distortion and bowl wabbling incident to the use of previous joints.

In the preferred embodiment of our improvements, a threaded joint is formed between the shell and closure, and a surface of the thread on one member is drawn into close contact with the surface of a thread on the other member; such contact being preferably effected by the engagement of bearings on the respective members having contacting surfaces normal to the axis of the bowl. The engagement of such bearing surfaces also effects and maintains the alignment or parallelism of the axes of the bowl and closure, this function of the bearing surfaces being of particular importance when the axial contact between the shell and closure is comparatively short, viz, less than the shell diameter.

The closure has formed thereon, on the opposite sides of its screw thread, cylindrical surfaces concentric with the axis of the bowl and engaging the shell wall to guide and steady the closure and assist in maintaining the rigidity of the joint and the alignment 40 of the closure axis with the axis of the shell. The outer terminus of the interstice between the shell and closure is sealed by packing compressed by a clamp secured to one of the members.

The characteristic features and advantages of our invention will more fully appear from the following description and the accompanying drawings illustrating the preferred embodiment thereof.

In the drawings, Fig. 1 is a longitudinal sectional view of a centrifuge having our improvements applied thereto; Fig. 2 is an enlarged sectional view of the upper part of the bowl shown in Fig. 1; Fig. 3 is a further

enlarged fragmentary view of the joint formed between the bowl shell and its closure; and Fig. 4 is a fragmentary view showing the sealing gasket and channel therefor.

As illustrated in the drawings, the frame A carries a bearing B on which is journaled a power driven pulley C having depending therefrom a flexible spindle D from which the bowl E is suspended. The mixture to be centrifuged is introduced into the bottom of the bowl through the feed nozzle F and the separated constituents are discharged through the top of the bowl to the covers G and H provided with suitable discharge spouts.

In accordance with our invention, the bowl top 1 has its lower portion or body 2 provided with a helical rib forming truncated external threads 4, and the upper part of the internal wall of the shell 3 is grooved to provide a helical rib forming threads 5 complementary to the threads 4. The top 1 and shell 3 are respectively provided with complementary bearings or shoulders 6 and 7 having surfaces normal to the axis of the bowl, the surface of the shoulder 6 being spaced from the nearest thread 4 a suitable distance, preferably greater than the base or width of such thread, and the surface 7 being spaced from the nearest thread 5 a suitable distance, preferably greater than the width or base of such thread. The engagement of the bearing surfaces 6 and 7 by screwing together the parts 1 and 3 draws into close contact the complementary surfaces 4' and 5' of the threads 4 and 5, thereby forming a tight joint which cannot be obtained when the threads of one part are allowed to lie in their normal position in the channel between the threads of the other part. The engagement of the bearing surfaces 6 and 7 also maintains in alignment the axes of the shell and its closure, which are brought into coincidence by the cylindrical surfaces 8 and 8'. The cylindrical surface 8 is formed on the closure 2 below the thread 4, and has a peripheral surface concentric with the bowl axis and makes a close slip fit with the inner cylindrical wall of the shell below the thread 5. The cylindrical surface 8' is formed on the closure 2 above the thread 4, and its peripheral surface is concentric with the bowl axis and makes a close slip fit with the cylindrical

bearing 12 formed in the shell above the thread 5.

The interstice between the bearing surfaces 8' and 12 is sealed by an elastic packing, such as a rubber gasket 11, seated in the annular channel 9 formed by complementary grooves in the closure and shell, the packing being firmly seated in the channel and against the annularly scored or indented bottom 10 thereof by a clamp comprising a collar 13 screwed on the threaded boss 14 of the bowl neck and a peripheral flange or ring 15 registering with and compressing the gasket.

15 It will be understood that in assembling the bowl, the head 2 is slipped in the shell 3, the pilot 8 forming a guide for effecting the proper engagement of the threads 4 and 5. The relative rotation of the parts 1 and 3 20 brings the bearing surfaces 6 and 7 into contact, and thereby brings the threaded surfaces 4' and 5' into close engagement. The disengagement of the shell and head may be prevented by engaging a stud or screw therein. The packing or gasket 11 is then placed 25 in the channel 9 and compressed therein by the clamp 15 by screwing the collar 13 down on the boss 14. A joint so formed is devoid of the play which results from the insertion 30 of an elastic packing between the metallic surfaces forming the joint, and the packing is protected from the effects of hot and heavy substances flowing through the bowl.

The bowl head may be provided with a 35 plurality of suitable effluent passages, such as indicated at 16, and the bowl is so designed as to rotate on a vertical axis and be supported and driven entirely through its head. By our construction, the torque and 40 thrust of the rapidly rotating bowl are transmitted directly between metallic bearing surfaces of the shell and head, with avoidance of side sway of the bowl, or leakage of the substance undergoing centrifugal treatment.

45 It will of course be understood that the joint between the shell and its bottom closure may be made in the same way as is here in described with reference to the shell and its top closure.

50 Having described our invention, we claim:

1. A centrifuge bowl comprising a shell and a head having complementary screw threads and a gasket sealing the external ter-

minus of the interstice between said shell and head.

55

2. A centrifugal bowl comprising a shell and a head, a gasket sealing the external terminus of the interstice between said shell and head, and a clamp having a threaded connection with one of said members and 60 pressing said gasket.

3. A centrifugal bowl comprising a shell having a thread therein; a head having a pilot engaging the inner wall of said shell, a thread engaging the thread of said shell, 65 and a bearing surface normal to the axis of the bowl and engaging a complementary surface of said shell; said shell and head having grooves therein forming a channel; a gasket seated in said channel; and means 70 for pressing said gasket in said channel.

4. A centrifuge bowl comprising a shell and a head forming a channel having a scored bottom, a gasket seated in said channel and means for pressing said gasket 75 against said bottom.

5. A centrifuge bowl comprising a shell and a head, packing sealing the joint between said shell and head, and a clamp threaded on an outer wall of one of said 80 members and pressing said packing against said joint.

6. A centrifugal bowl comprising a shell having a head sleeved in an end thereof, a packing sealing the external terminus of the 85 interstice between said shell and head and a ring sleeved on said head and pressing said packing.

7. A centrifuge bowl comprising a shell and a head, one of said members being 90 threaded into the other, a gasket sealing the joint between said members, and a clamp connected with one of said members and forcing said gasket in place.

8. A centrifuge comprising a depending 95 driven spindle, a head suspended from said shaft, and a shell suspended from said head, said shell and head having complementary engaging screw threads, and a gasket exterior to said shell and sealing the joint between said shell and head.

In testimony whereof we have hereunto set our names this 31 day of Aug., 1925.

LEO D. JONES.
ARTHUR U. AYRES.
